CAN PUNCTURING AND SEALING DEVICE

Arthur B. Spitzer, Canton, Ohio

Application June 24, 1936, Serial No. 87,075

6 Claims. (Cl. 220—51)

My invention relates to improvements in puncturing and sealing devices for cans, particularly milk cans, and the primary purpose thereof is to provide a simply constructed, efficient device of the character indicated which may be readily and securely clamped to the top of the can and embodying can-puncturing devices operative to puncture sealing and unsealing positions, respectively, and a bail-like handle for carrying the can and operating said devices and adapted to lie parallel with the top of the can in either position of said devices out of the way when the can is deposited upon a shelf or in a refrigerator or the like.

Other objects are to provide a device of the character and for the purpose above set forth which is strong and durable, easy to operate in puncturing a can, and comparatively inexpensive to manufacture.

Other and subordinate objects, together with the exact nature of my improvements, will become readily apparent as the following description proceeds and upon reference to the drawing accompanying and forming part of the specifications.

In said drawing:

Figure 1 is a view in vertical section of the usual form of milk container or can equipped with my invention.

Figure 2 is a view in side elevation illustrating the puncturing devices in unsealing position.

Figure 3 is a view in top plan.

Figure 4 is a view in side elevation, partly in section, illustrating the parts in puncturing and sealing position, and

Figure 5 is a view in perspective of a clamping member for securing the bail or handle and the puncturing devices to the can.

Referring to the drawing by numerals, my invention in its preferred embodiment comprises a clamping member 1 formed of a length of rod-like resilient metal bent upon itself to provide a straight bridge portion 2 designed to overlie the top end of a can 3 and having right-angled loop ends 4, comprising outer and inner parallel arms 5 and 6 respectively, the inner arms 6 terminating in inner right-angled jaws 7 designed to overlie the edge of the top of the can at diametrically opposite points thereon.

The inner arms 6 and the jaws 7 are spaced slightly from the outer arms 5 and the bridge portion 2 to spring outwardly of the can 3 and the inner arms 6 are shouldered, as at 8, to take under the usual flange 9 at the end of the can.

A substantially triangular bail 10, having side

arms 11, is swingably mounted on the bridge portion 2 intermediate the jaws 7 by looping the ends of the side arms 11 around said portion, as at 12. The looped portions 12 are disposed adjacent to the inner ends of the jaws 7 to prevent side-play of the bail 10. The looped portions 12 terminate in puncturing devices in the form of substantially semi-circular sharp-pointed punches 13 curving back against the side arms 11 and disposed in planes at right angles to the axis of the bridge portion 2.

The clamp 1 is designed to be secured to the top end of the can 3 by sliding it over said end until the jaws 7 are in diametrically opposite positions on the can top, the shoulders 8 engaging under the flange 9 and the inner ends of the jaws 7 overlying the edge of the can top. In this connection it is to be noted that the clamp 1 is to be made in different lengths for cans of different diameters and that the inner arms 6 and jaws 7 have a play and are sufficiently reactive to clampingly engage the top edge of the can. The relation of the bail 10 and punches 13 is such that when the bail is swung flat against the top of the can 3 on one side of the clamp 1, the punches 13 will assume an upstanding position clear of the can top, as illustrated in Figure 2, and when the said bail is swung to the other side of the can top into a position substantially parallel therewith, the punches 13 will be forced into the can top to pierce the same at opposite sides thereof and seal the punctures therein.

The looped portions 12 of the bail arms 11 are provided with a pair of shoulders 14 and 15 designed to engage the inner ends of the jaws 7 to limit movement of the bail 10 in the described positions thereof. This feature provides for holding the bail 10 in a right-angled position relative to the ends 4 of the clamp 1 on one side of said clamp out of interfering position when the clamp is being applied to the can. In the opposite, the puncturing and sealing position of the bail 10, overthrow movement of the bail 10 and punches 13 is prevented so that the punches 13 cannot tear the top of the can and thus impair their sealing function.

As will be clear, the bail 10 functions in the dual capacity of a punch-operating member and a handle for the can to which the invention is attached.

The foregoing description will, it is believed, suffice to impart a clear understanding of my invention.

It is to be understood, however, that the details described in the foregoing are illustrative of a

preferred embodiment of my invention only and that right is herein reserved to modifications of such details falling within the scope of the claims appended hereto.

5. What I claim is:

1. A puncturing and sealing device for attachment to the top of a can comprising, a clamp including a straight bridge portion adapted to overlie the top end of the can and having right-angled resilient end arms for clamping the top edge of the can therebetween, and a bail member comprising a pair of side arms having end portions looped around said bridge portion, whereby said bail is swingable on said bridge portion, said looped portions terminating in curved sharp-pointed punches swingable into and out of the top of the can simultaneous with the swinging of said bail.

2. A puncturing and sealing device for attachment to the top of the can and comprising, a clamp including a straight bridge portion adapted to overlie the top end of a can and having right-angled resilient end arms for clamping the top edge of the can therebetween, and a bail member comprising a pair of side arms having end portions looped around said bridge portion, whereby said bail is swingable on said bridge portion, said looped portions terminating in curved sharp-pointed punches bent back upon the side arms of said bail for swinging movement therewith into and out of the top of the can.

3. A puncturing and sealing device for attachment to the top of the can and comprising, a clamp including a straight bridge portion adapted to overlie the top end of a can and having right-angled resilient end arms for clamping the top edge of the can therebetween, and a bail member comprising a pair of side arms having end portions looped around said bridge portion, whereby said bail is swingable on said bridge portion, said looped portions terminating in curved sharp-pointed punches bent back upon the side arms of said bail for swinging movement therewith into and out of the top of the can, said looped portions being disposed adjacent to said end arms whereby side-play of the bail on the bridge portion is prevented.

4. A puncturing and sealing device for attachment to the top of the can and comprising, a clamp including a straight bridge portion

adapted to overlie the top end of a can and having right-angled resilient end arms for clamping the top edge of the can therebetween, and a bail member comprising a pair of side arms having end portions looped around said bridge portion, whereby said bail is swingable on said bridge portion, said looped portions terminating in curved sharp-pointed punches bent back upon the side arms of said bail for swinging movement therewith into and out of the top of the can, and co-operating devices on said looped portions and said ends of the bridge portion, respectively, for limiting movement of said bail in either position thereof.

5. A puncturing and sealing device for attachment to the top of a can and comprising, a clamp including a straight bridge portion adapted to overlie the top end of the can and having right-angled looped ends comprising inner and outer resilient arms laterally spaced from each other, the inner arms terminating in right-angled jaws adapted to overlie the edge of the top of the can to clampingly engage the same at diametrically opposite points thereon, and a bail member comprising a pair of side arms having end portions looped around said bridge portion adjacent to said jaws whereby said bail is swingable on said bridge portion, said looped portions terminating in curved sharp-pointed punches swingable by said arms into and out of the top of the can.

6. A puncturing and sealing device for attachment to the top of a can having an end flange and comprising, a clamp including a straight bridge portion adapted to overlie the top end of the can and having right-angled looped ends comprising inner and outer resilient arms laterally spaced from each other, the inner arms terminating in right-angled jaws adapted to overlie the edge of the top of the can to clampingly engage same at diametrically opposite points thereon, and a bail member comprising a pair of side arms having end portions looped around said bridge portion adjacent to said jaws whereby said bail is swingable on said bridge portion, said looped portions terminating in curved sharp-pointed punches swingable by said arms into and out of the top of the can, said jaws having shoulders thereon adapted to take under said flange on the can.

ARTHUR B. SPITLER.
